UNITED STATES PATENT OFFICE

2,478,133

PROPAGATION OF RADIO WAVES
THROUGH A TUNNEL

John P. Shanklin, Baltimore, Md.

Application July 31, 1946, Serial No. 687,479

1 Claim. (Cl. 250—33)

1

This invention relates to a method and means for propagating radio waves through constricted natural or man-made passageways, such, for example, as a railway tunnel.

Difficulties have been experienced in transmitting radio waves through railway tunnels at frequencies desired for railway communication purposes. However, while failure normally attended attempts at those frequencies, it was noted that communication over considerable distances could be established at much higher frequencies.

At frequencies below and even somewhat above the wave guide cut-off frequency of the structure from a dimensional viewpoint, the high dielectric constant and low resistivity of the material normally composing the walls of the structure cause a great deal of the energy to be refracted into the walls and lost. Only at frequencies at which the angle of incidence of the transmitted waves is such as to insure almost complete reflection from the wall will attenuation be negligible.

It is an object of this invention to improve the propagation of radio waves through natural or man-made passageways, such as railway tunnels.

It is another object of this invention to provide a method and means for transmitting a radio wave through such passageways at any desired frequency within a wide range without an objectionable amount of attenuation.

It is a further object of this invention to provide for the efficient propagation, through such a passage, of radio waves at frequencies below the cut-off frequency of the passageway when acting as a wave-guide.

It is still another object of this invention to provide means affecting propagation through such a passageway without utilizing the properties of the passageway as a wave-guide.

It is a still further object of this invention to provide means for propagating radio waves through such a passageway while preventing substantial energy absorption by the walls thereof.

Other objects and advantages of the invention will become apparent from a consideration of the following specification, when taken together with the accompanying drawing, in which:

Fig. 1 is a cross sectional view of a pair of parallel conductors constituting a balanced transmission line, showing a representation of the electrostatic field existing between them;

Fig. 2 is a diagrammatic view, in cross section, of a portion of a tunnel wall and of a railway communication type antenna, together with propagation means embodying the invention, and;

Fig. 3 is a perspective view of a railway tunnel

2

entrance, showing the termination structure of a wave propagation means embodying the invention.

The objects and advantages of the invention are attained by suspending a metallic ground plane structure below the ceiling of the tunnel to shield the transmitted wave from the tunnel wall material and mounting below, in parallelism with the ground plane, an insulated conductor which, with the ground plane structure, form a transmission line.

Referring now more particularly to the drawing, there is shown in Fig. 1 a diagram illustrating the development of a transmission line of the type contemplated by the invention. In this figure is shown a representation of the cross section of two wires 10 and 11 of a balanced transmission line. As these wires carry equal voltages of opposite polarity a plane *b* of zero potential, or a virtual ground plane, exists between them. If wire 11 is removed and a sheet conductor placed at *b*, an unbalanced transmission line results whose surge impedance is one-half that of the original line. The lines *c* represent the electrostatic lines of force constituting the field about the two conductors. Each of the conductors is spaced from the plane *b* by a distance *e*.

Fig. 2 illustrates the employment of such an unbalanced transmission line in accordance with the invention. Suspended below the ceiling 16 of the tunnel is a metallic ground plane structure composed of the parallel wires 12. These wires lie in a plane indicated by the reference character *b*, which may be considered as the equivalent of the ground plane *b* of Fig. 1. Suspended below the ground plane structure and in parallelism with the plane *b*, in the location corresponding to the conductor 10 of Fig. 1, is a conductor 10. The conductor 10 is insulated from the ground plane structure and the walls of the tunnel. The ground plane construction comprising the wires 12 simulates a sheet of conducting material and acts as a shield to prevent the absorption of the radiated wave by the material of the tunnel wall. Each of the wires 12 defines a plane with the conductor 10, the planes so defined being angularly separated by equal angles. This particular feature is not essential but makes for economy of wire use for optimum shielding results. To obtain effective shielding the ratio *d/e* should be 2 or greater where *d* is the distance from the center to the edge of the array of wires 12, and *e* is the distance between the conductor 10 and the plane *b* containing the conductors 12.

The greater the number of wires 12 employed the lower will be the attenuation.

Fig. 2 also illustrates the positional relationship between the unbalanced transmission line structure just described and a train-borne antenna 13 of a type used in railway communication service. The antenna 13 comprises a feed line 17 of the coaxial type, the inner conductor terminating in its upper portion in a quarter-wave length vertical member 15 and the outer conductor terminating in its upper portion in a ground plane of quarter-wave radius. As will be seen, the antenna 13 will move along the length of the unbalanced transmission line with the member 15 positioned directly below the conductor 10 and spaced uniformly therefrom by an amount to insure satisfactory coupling therebetween, as indicated by the construction lines c representing the electrostatic lines of force in the field generated during transmission or reception with antenna 13.

Communication may be established between two distant points in a tunnel by the use of an antenna of the type shown at 13 in Fig. 2 at both the transmitting and receiving points. However, unless the transmission line is terminated at each end in its surge impedance, standing waves will be set up on the line which will result in flutter if used with a moving train.

By terminating the transmission line at each of its ends in an antenna, communication may be had between any point in the tunnel and a distant surface station. Fig. 3 illustrates one manner of executing such a termination. In this figure there is shown an end of a train 18, equipped with a communication antenna 13, emerging from a tunnel 16 which is provided with an unbalanced transmission line comprising the wires 12 and the insulated conductor 10, as described in Fig. 2. Here the line is terminated in a directional antenna which is directed toward the track approaching the tunnel. The directional antenna shown by way of example is a vertically polarized rhombic antenna comprising the legs 19 and 20, the surge impedance of the antenna being made equal to that of the transmission line. The rhombic antenna incorporates a resistive termination which equals its surge impedance. This resistance is not shown. It is necessary to supply a point of zero voltage to which the resistance may be connected and such point is supplied in this case by a quarter-wave radius, ground plane 21. A similar termination will be employed on the other end of the transmission line.

The system just described may be employed not

only in tunnels but also in cuts and canyons or wherever a point of poor communication is found to be present due to the conditions which were described above. For outdoor use a two-wire balanced line may be used because of its cheaper construction. However, the radiation from the upper wire will represent lost energy. In the systems described the direction of energy transmission may be reversed at will with equal transfer of energy in either direction.

While the disclosure of the invention has been restricted to those embodiments which are now preferred, many variations of form and arrangement falling within the scope of the invention as defined by the appended claim, will occur to those skilled in the art. It should therefore be understood that the scope of the invention is not to be considered as limited to the embodiments described herein, but only by the scope of the appended claim.

What is claimed is:

Means for the propagation of radio waves along a railway tunnel, with respect to a rail mounted antenna traversing said tunnel, which comprises a conductor electrically insulated with respect to said tunnel, said conductor extending through said tunnel and spaced in coupling relation to said antenna throughout its traversal of said tunnel, a ground plane structure paralleling said conductor and positioned between said conductor and the wall of said tunnel, whereby said ground plane structure shields said waves from absorption by the walls of said tunnel, said conductor and said ground plane structure constituting an unbalanced transmission line, and a termination at each end of said line, said termination having a surge impedance equal to that of said line, said termination comprising a directional antenna located outside an entrance to said tunnel, said directional antenna being directed along the track approaching said tunnel, and means terminating said antenna, said means comprising a ground plane.
